[57] **CLAIM**

The ornamental design for a game spinner, as shown
and described.

DESCRIPTION

FIG. 1 is a perspective view of a game spinner showing
our design;

FIG. 2 is a side elevational view thereof, the opposite
side being a mirror image of such view;

FIG. 3 is a front elevational view of a game spinner
showing our design; and

FIG. 4 is a rear elevational view of such game spinner.

FIG. 1

FIG. 2

FIG. 3

FIG. 4
